UNITED STATES PATENT OFFICE.

LEO SOLINGER, OF NEW YORK, N. Y., ASSIGNOR TO EAGLE PENCIL COMPANY, OF NEW YORK, N. Y., A CORPORATION OF DELAWARE.

DESIGN FOR A PENCIL.

Application filed July 20, 1925. Serial No. 14,142. Term of patent 14 years.

To all whom it may concern:

Be it known that I, LEO SOLINGER, a citizen of the United States of America, residing at New York, in the county and State of New York, have invented a new, original, and ornamental Design for Pencils, of which the following is a specification, reference being had to the accompanying drawing, forming part thereof.

Fig. 1 is an elevation showing in full one of the four sections or portions of the design.

Fig. 2 is an enlarged fragmentary view illustrating two of the four sections or portions of the design.

Fig. 3 is, like Fig. 2, an enlarged fragmentary view, but illustrates the other two of the four portions of the design, one of the two being the same as is shown in full in Fig. 1.

A dominate feature of my design resides in the distinctively colored panels in the tip which harmonize with the colored panels in the body of the pencil.

I claim:

The ornamental design for a pencil, substantially as shown and described.

In testimony whereof I hereto affix my signature.

LEO SOLINGER.
